UNITED STATES PATENT OFFICE

90,733

DESIGN FOR AN ATOMIZER

John G. Rideout, Toledo, Ohio

Application June 14, 1933. Serial No. 48,401

Term of patent 7 years

To all whom it may concern:

Be it known that I, JOHN G. RIDEOUT, a citizen of the United States, and resident of Toledo, county of Lucas, State of Ohio, have invented a new, original, and ornamental Design for an Atomizer, of which the following is a specification, reference being had to the accompanying drawing forming a part thereof.

In the drawing, the single figure is a side elevation of an atomizer showing my new design.

The essential feature of the design resides in the shape of the liquid-containing portion of the atomizer as shown in full lines in the drawing.

I claim:

The ornamental design for an atomizer, substantially as shown and described.

In testimony whereof I have hereunto signed my name to this specification.

JOHN G. RIDEOUT.
